PISTON EXPANDER

Dallas M. Smith, Kirkwood, Mo., assignor to
McQuay-Norris Manufacturing Company, St.
Louis, Mo., a corporation of Delaware

Application June 14, 1944, Serial No. 540,253

7 Claims.

(Cl. 309—12)

This invention relates generally to piston expanders and particularly to such an expander as may be inserted in the piston under treatment without the necessity of removing the wrist pin.

Heretofore, piston expanders have been provided in a variety of forms which, for the most part, necessitated the removal of the wrist pin in order to position the expander within the piston. A type of piston expander which has been used to a substantial extent, however, and which does not require removal of the wrist pin in order to position the expander within the piston, involves the driving of an element into wedging engagement between the sides of the wrist pin bosses and the interior of the thrust face of the piston. The use of such an expander as that last referred to results in the setting up of tremendous strains between the wrist pin boss and the portions of the skirt thereadjacent with the consequence that not infrequently fractures occur in that region.

The object of the present invention, generally stated, is to provide a piston expander of the character which is insertable without removal of the wrist pin and which does not, in operation, transmit thrust to the wrist pin boss.

Other objects will become apparent to those skilled in the art when the following description is read in connection with the accompanying drawing, in which:

Figure 1 is a perspective view of an expander constructed in accordance with one embodiment of the present invention;

Fig. 2 is a sectional view of a piston showing the expander of Fig. 1 in position therein;

Fig. 3 is a detailed view showing the anchorage provided on the expander of Figs. 1 and 2 for holding the expander in position;

Fig. 4 is a view in side elevation of an expander constructed in accordance with another embodiment of the present invention;

Fig. 5 is a plan view of the expander shown in Fig. 4;

Fig. 6 is a sectional view taken along lines 6—6 of Fig. 5;

Fig. 7 is a fragmentary view corresponding, in part, to Fig. 2 and showing the expander of Figs. 4 to 6, inclusive, in position in a piston;

Fig. 8 is a view in side elevation of a further modification; and

Fig. 9 is a view in side elevation of a modification of the form shown in Figs. 1 and 2.

In accordance with the present invention, generally stated, a piston expander is formed of a generally oval shape having portions adjacent

the ends of its major axis for engaging the interior thrust faces of a piston. Between the portions which engage the interior of a piston connecting portions are provided which are cut away in order to accommodate the wrist pin bosses—sufficient material, however, remaining below the cutaway recess to transmit the expanding forces chordally across the piston from one thrust face to the other without requiring that the wrist pin bosses receive the reaction of the expanding forces.

The present invention further contemplates that such a piston expander be anchored in position by the provision thereon of yieldable projections, which may be slightly distorted in the process of inserting the expander within the piston but which, when they have passed obstructions existing in the piston structure, expand to prevent removal of the expander therefrom. For example, such projections may be provided in a form which will enter a horizontal slot or a horizontally slotted piston, or may be provided in a form which will engage over another interior projection of the piston such as the wrist pin boss or interior ribbing; it being noted in this connection, however, that when the engagement is with the wrist pin boss, the expanding thrust is not sustained thereby but merely the forces of inertia which tend to dislodge the expander from position.

Referring now to Figs. 1, 2, and 3 of the drawing for one illustrative embodiment of the present invention, the expander is composed of a band of metal 1 formed to an oval configuration as shown, so as to provide substantially large bearing faces 2 and 3 adapted to engage the interior of the thrust faces of the piston. Between the bearing faces 2 and 3 of the expander are connecting portions 4 and 5 which are cut away, as shown clearly in Fig. 1, to provide a U-shaped recess of size sufficient to accommodate the wrist pin boss and prevent the expanding forces from being sustained by the wrist pin boss. In the embodiment shown in Fig. 1 the expander is formed of a single strip of metal cut out as shown and welded together at 6.

In order to anchor the expander within the piston a resilient tongue 7 having a turned over lip 8 is provided in one or both of the bearing surfaces 2 and 3. The tongue 7 is sufficiently flexible that it will yield inwardly, as shown in the dotted line position in Fig. 3, to an extent sufficient that the outer edge of the lip 8 will move upwardly along the inside wall of the piston 55 until the horizontal slot 9 of the piston shown

in Fig. 2 is reached. At this point the inherent resilience of the tongue 7 forces the lip 8 outwardly into the slot 9 where the lip terminates short of the actual bearing surface of the piston. With the expander in this position the cutout portion, as clearly shown in Fig. 2, clears the wrist pin boss 10 so that none of the expanding force is sustained by the wrist pin boss.

In lieu of welding the ends of the band of metal together as suggested above at 6, an arrangement of interlocking tongues as shown at 11 in Fig. 9 may be provided. This arrangement has the virtue of permitting the ends to be separated in order to place the expander over the slender portion of a connecting rod, whereas in the case of the embodiment shown in Fig. 1, where the ends are permanently connected, it is sometimes impossible to pass the expander over the connecting rod bearing.

In the embodiments shown in Figs. 4 to 7, inclusive, the expander is in general identical with that previously described, being provided with bearing surfaces 2 and 3 and connecting portions 5 and 6 each having cutouts to accommodate and clear the wrist pin boss; but in lieu of the anchorage means shown in the previous embodiment the present embodiment is provided with fingers 12, of which in the embodiment shown there are four, but one will frequently suffice. The fingers 12 are inclined in two directions, as clearly shown in Figs. 5 and 6, so as to be cammed inwardly when the expander is inserted from the bottom of the piston past the wrist pin boss. When in the process of insertion the fingers 12 have cleared the boss 10 they spring outwardly, and, being then disposed as shown in Fig. 7 above and within the horizontal diameter of the boss, securely anchor the expander in position so that it cannot be displaced by the forces of inertia.

In the embodiment shown in Fig. 8 a further example of anchorage means is disclosed. In this instance a latch piece 13 is pivoted at 14 to that portion of the expander which will extend above the wrist pin boss. The length and configuration of the latch bar 13 is so designed that the same will not interfere with movement of the expander into proper position within the piston. This, however, does not require that the latch bar 13 assume an upright position until the expander reaches its ultimate position within the piston. On the contrary, after the upper end of the latch bar 13 has passed beyond the horizontal diameter of the wrist pin boss, the latch bar may begin to be swung in a counterclockwise direction about its pivot so as to clear the interior head of the piston and finally assume a position whereat it will extend across the top of the pin boss or other projection on the interior of the piston and be arranged for engagement with a suitable latch lug 15 for holding the latch bar 13 in anchoring position, which would be substantially horizontal as shown in Fig. 8.

From the foregoing description those skilled in the art will readily understand the construction and operation of the expander as shown herein and appreciate that the expander, while readily insertable without removal of the wrist pin, may nevertheless be securely located within the piston without necessitating the setting up of thrusts the reaction of which must be taken by the pin boss.

While several forms of anchorage means have been shown in the accompanying drawing, it is to be distinctly understood that the present invention is not limited to the details of the forms

herein shown but that a variety thereof may be provided without departing from the spirit of this invention or the scope of the appended claims.

5 What is claimed is:

1. A piston expander comprising, a generally oval body having portions at the ends of its major axis for engaging the interior surface of piston faces, connecting portions therebetween, a U-shaped cutout open at the upper edge in each of said connecting portions to accommodate the projections on the interior of the piston.

10 2. A piston expander comprising, a generally oval body having portions at the ends of its major axis for engaging the interior surface of piston faces, connecting portions therebetween, a U-shaped cutout open at the upper edge in each of said connecting portions to accommodate the projections on the interior of the piston, and means for anchoring the body within the piston.

15 3. A piston expander comprising, a generally oval body having portions at the ends of its major axis for engaging the interior surface of piston faces, connecting portions therebetween, a U-shaped cutout open at the upper edge in each of said connecting portions to accommodate the projections on the interior of the piston, and resilient means on the body for anchoring engagement with an interior fixed part of a piston.

20 4. A piston expander comprising, a generally oval body having portions at the ends of its major axis for engaging the interior surface of piston faces, connecting portions therebetween, a U-shaped cutout open at the upper edge in each of said connecting portions to accommodate the projections on the interior of the piston and lugs on the body positioned to encounter obstructions on the interior of the piston while being inserted, said lugs being arranged to yield to pass such obstructions and to resume normal position beyond such obstructions thereby to anchor the body within the piston.

25 5. A piston expander comprising, a generally oval body having portions at the ends of its major axis for engaging the interior surface of piston faces, substantially chordal connecting portions, a U-shaped cutout open at the upper edge in each of said connecting portions to clear the bosses of the piston, and a lug adapted to clear the boss during insertion but to anchor above the boss when completely inserted.

30 6. A piston expander comprising, a generally oval body having portions at the ends of its major axis for engaging the interior surface of piston faces, substantially chordal connecting portions, a U-shaped cutout open at the upper edge in each of said connecting portions to clear the bosses of the piston, and a lug arranged to enter the slot of the piston when the body is completely inserted therein.

35 7. A piston expander comprising, a generally oval body having portions at the ends of its major axis for engaging the interior surface of piston faces, substantially chordal connecting portions, a U-shaped cutout open at the upper edge in each of said connecting portions to clear the bosses of the piston, and a movable latch member connected with the body at one side of the cutout and arranged for interlocking engagement with the body at the other side of the cutout, said latch when engaged extending crosswise of the piston above the boss.
